CLAIM

The ornamental design for a light fixture, as shown and described.

DESCRIPTION

FIG. 1 is top perspective view of a lamp showing my new design;

FIG. 2 is a side elevation view thereof, the views from all sides being identical due to the lamp's symmetry about a vertical axis;

FIG. 3 is a top plan view thereof; and,

FIG. 4 is a bottom plan view thereof.

The broken lines represent portions of the light fixture that form no part of the claimed design.
